UNITED STATES PATENT OFFICE.

ROBERT S. RILEY, OF PROVIDENCE, RHODE ISLAND, ASSIGNOR TO AMERICAN ENGINEERING COMPANY, OF PHILADELPHIA, PENNSYLVANIA, A CORPORATION OF PENNSYLVANIA.

FURNACE.

1,156,628.

Specification of Letters Patent.

Patented Oct. 12, 1915.

Application filed March 2, 1909. Serial No. 480,823.

To all whom it may concern:

Be it known that I, ROBERT S. RILEY, of Providence, in the county of Providence and State of Rhode Island, have invented 5 certain new and useful Improvements in Furnaces, of which the following is a specification.

This invention relates to furnaces and automatic stokers of the inclined underfeed 10 type, in which fuel is forced through vertical retorts having inclined mouths, in a horizontal direction into the furnace, beneath the incandescent bed of fuel.

The object of the present invention is to 15 secure a more complete control of the feed of the fuel so that fresh fuel may be fed to the lower part of the fuel bed under all circumstances, and also to increase the capacity of feeding the fuel.

20 Another object is to provide an improved construction of wind box and air inlet which will allow air to be carried into the furnace with less resistance than heretofore, will eliminate danger of injury by excessive heat 25 changes to the walls of the retorts, and will enable repairs of whatever injury may result to be made with very little inconvenience and at an expense which is practically nothing.

30 Briefly stated, the invention consists in provisions for admitting fresh fuel directly to the bottom of the retort, so that it may be acted on in the first instance by the lower of a vertically-arranged series of fuel-feeding 35 plungers, without requiring first to be pushed a certain distance into the retort by the upper plunger.

It also consists in a frame, of which a series placed upon one another forms at 40 the same time part of an air conduit and part of the fuel retort.

Of the accompanying drawings,—Figure 1 represents a longitudinal sectional view of the forward end of a furnace structure having my invention applied thereto, showing 45 also a portion of a steam boiler. Fig. 2 represents a sectional view of part of the furnace on line 2—2 of Fig. 1. Fig. 3 represents a perspective view of one of the 50 frames.

The same reference characters indicate the same parts in all the figures.

In the drawings, 2 represents one of the walls of a furnace inclosure, preferably the 55 front wall thereof. Extending through the

wall 2 is a structure consisting of a horizontal bottom 3 and a plurality of vertical partitions 4 and 5. Alternate pairs of the vertical partitions inclose vertical fuel passages or retorts 6 which open at their rear 60 into the furnace inclosure and serve to conduct fuel thereinto and to contain the fuel while the same is being distilled, and the gases being driven off therefrom and the residue converted into coke.

At the front of each retort are plungers 7 and 8 which reciprocate horizontally, one above the other, and serve to force fuel issuing from the hopper 9 into the furnace beneath the bed of burning fuel already therein. These plungers are reciprocated by mechanism which is indicated in the drawings, and the lower plunger is given a stroke which may be varied and is preferably less than that of the upper plunger. The actuating mechanism for the plungers is not part of the present invention and a particular description of the same is not necessary to enable the invention to be understood. The main feature of the invention is the provisions by which I am enabled to feed fresh fuel directly to the lower part of the fuel bed in order to govern the thickness and inclination of the same more effectively than has hitherto been possible.

It will be noted that the lower plunger is almost directly under the upper plunger, being advanced but slightly beyond the same, and that directly below the opening or passage 10 through which the fuel is admitted from the hopper 9, there is a passage 11 which extends to the bottom of the retort behind the lower plunger. The two passages 10 and 11 form a continuous chute which allows the fresh fuel to drop from the hopper directly to the bottom of the retort, and to form a column therein extending through the entire height of the chute into the hopper. This column is so located that both plungers may act simultaneously upon it, feeding the upper and lower portions thereof separately in approximately parallel horizontal streams into the furnace. There is a partition 12 between the paths of the plungers, the upper part of which extends downward from the bottom of the upper plunger path, and the lower part of which slants upward from the top of the lower plunger path. This partition separates and defines the fuel streams

propelled by the several pushers, but allows them to spread and merge with one another before being ejected from the retort and issuing into the furnace inclosure. This 5 part of the invention is of great practical importance, since it insures a positive feed of fuel directly by the lower plunger under all circumstances, and by causing fuel to be fed simultaneously by both plungers, 10 permits a more rapid feed of fuel and an increased capacity of combustion. It enables fuel to be supplied as fast as it is consumed when the furnace is forced to its highest capacity. 15 I do not limit my invention to the combination of two plungers only in a furnace of the character described, but contemplate the use of more than this number, and declare that my invention includes within its scope 20 any number of plungers arranged in vertical series in each retort, with provision for allowing the fresh fuel to fall where it can be acted on in the first instance by all the plungers, without requiring to be first discharged by the upper plunger. The plungers constitute pushing means which propel the fuel from the front of the retorts to and out of the mouths at the rear thereof. Any pushing means capable of accomplishing 25 this result may be used in place of the specific plungers here illustrated, and accordingly I do not limit the scope of the invention to cover only cylindrical plungers. The term "plunger" is employed for illustration only and not as a term of limitation, and therefore it is to be understood that wherever I use this term in the specification and claims, I intend to include also any pushing devices whatever capable of propelling the fuel as described. 40

In the spaces between the retorts are set the ends of frames 13 which form continuations of the retort walls, and consist of connected side members which form a continuous closed outline, but are open from top to bottom. These frames are placed one upon another at the rear of the partitions 4 and 5, the lowermost frame being placed upon a transversely extending air trunk 14. The 45 side members of the frames thus piled up constitute in effect the sides of an air conduit which is located at the mouth of each retort. Each frame consists of the side members 15 16, the transverse end member 17, which is substantially perpendicular to the side members, and converging rear end portion 18. The apex of the latter portion points toward the rear of the furnace, while the front end member 17 is set between the 50 walls of the retorts. The side members 15 16 thus project substantially in line with the walls of the retorts a considerable distance into the furnace, and form continuations of the retorts. The converging rear portion 55 has perforations 20 which provide openings

for the outlet of the air emitted to support combustion. The combustion does not occur until the fuel has reached or passed the openings, and the heat within the retorts is not great at the rear terminations of the 70 partition plates 4 and 5. Consequently, these plates which are ordinarily made of cast metal, are not subjected to great variation of temperature, and so are not liable to warp and crack. The only metal parts 75 which are subjected to severe heat effects are the points of the frames themselves, and as these frames are independent of other parts of the furnace construction, any one may be removed and a new one substituted, without 80 requiring the furnace to be dismantled, and at an expense which is so slight as to be negligible.

By reason of the fact that the frames themselves constitute the air conduit and 85 have no top plates, with the exception of the uppermost plate 13^a, no frictional resistance is offered to the flow of air through the conduit, but a uniform pressure may be maintained throughout the entire extent of each 90 of such frame conduits, and the air issues with approximately equal force and velocity through all of the openings 20. Each frame at the rear end has a hook 21 which locks into the end of the frame beneath, a notch 95 22 being provided in the upper side of each frame to receive the hook of the frame above, and at their front ends there are shoulders 23 which engage the sloping edges 24 of the partitions. These hooks and the 100 partition edges cause the column of frames to slant, and thus define the slope of the retort mouths. The slant is such that the plane of the retort mouths extends downwardly and rearwardly from the upper limit 105 its to the floors or bottoms of the retorts and crosses the lines in which the plungers feed the fuel. Thus the fuel after emerging from the retorts forms a continuous sloping bed, the slope of which is sufficient to permit a gravity feed of ash from the upper surface of the bed to the dumping plates or grates at the rear.

At the rear of the furnace are dumping plates 25 upon which ash and other combustible products of the fuel collect. These plates are held up by bars 26 which may be withdrawn from time to time to allow the plates to dump and discharge the matter resting thereon. 115

An important feature of the invention is the particular construction of the retorts and the manner in which the same are assembled in the furnace. Each retort is an independent box-like casting having the 120 bottom 3, side walls 4 and 5, as previously described, top arched wall 30 having the opening 10 to receive the fuel, and the front wall 31 provided with the tubular guides 32 and 33 for the plungers. At the rear end 125 130

of the retort is a vertical web 34 stiffened by the side webs or brackets 35. This web lies beside the air trunk 14 which, as before stated, extends transversely of the furnace, and is bolted to the trunk. Thus the latter supports and retains the rear ends of the retorts, their forward ends being supported by a girder 36. The spaces between the retorts are open, except for the frames 13 at their rear ends, so that when these frames are removed, openings are provided directly into the interior of the furnace and free access thereto is given.

I claim:—

15 1. A furnace, including an inclosure, a vertical fuel passage or retort of less width than the inclosure of the furnace and formed with an inclined rear mouth opening into the interior of the furnace, means for 20 admitting air on each side of the retort mouth, horizontally reciprocating top and bottom pushers in the front of said retort for feeding fuel therethrough, and an inlet above said pushers, the retort having a passage 25 extending substantially vertically directly from the inlet to the bottom of the retort in rear of said bottom pusher, whereby fuel may be forced into the lower portion of the fuel bed by the lower pusher without 30 being previously acted on by the upper pusher.

2. A furnace, a fuel guiding retort formed as a separate entity extending into the furnace and having upright side walls, fuel 35 feeding means in the forward portion of said retort arranged to travel back and forth in the general direction of the retort, and removable frames placed one upon another so as collectively to form conduits for air 40 and having emission apertures in their sides, the air conduits so formed being placed adjacent to the rear terminations of said walls and separated by approximately the width of the retort.

45 3. The combination of a furnace, a vertical retort having an inclined mouth opening into the furnace at the front thereof, backwardly and forwardly reciprocating pushers mounted at different levels in the forward 50 end of said retort to feed fuel therethrough, and a horizontal partition between said pushers terminating within the retort, the said retort having a fuel inlet at its top in rear of said plungers, and a passage extending past said partition beneath said inlet, whereby a stream of fresh fuel may be fed 55 by a lower pusher and merged with that fed by an upper pusher before issuing into the furnace.

60 4. An underfeed furnace including in its construction a retort having a substantially horizontal bottom and upright sides terminating in a sloping mouth, a fuel pusher arranged to travel back and forth in a line 65 adjacent to the bottom of said retort, a sec-

ond fuel pusher arranged to reciprocate back and forth in the upper part of the retort, and a fuel inlet opening into the forward end of the fuel passage and in rear of the first-named pusher, whereby green fuel 70 may be fed directly from the inlet to the rear part of the fuel bed without being subjected to the heat of the fire in the forward part of the furnace.

5. A furnace inclosure, a vertical fuel retort 75 passing through a wall of the furnace and opening within the furnace inclosure, and superposed frames situated at the sides of the retort mouth inside the furnace and forming air conduits for feeding air to the fuel, said frames having lateral openings for emission of the air.

6. A furnace including walls, a plurality of vertical partitions extending through a wall of the furnace, arranged in pairs, each 85 pair forming a horizontally extending retort, horizontally reciprocating fuel-feeding plungers in each retort, frames placed one upon another between adjacent retorts and extending beyond the inner termination 90 thereof, inclosing an air duct and forming the mouths of the retorts, and means for admitting air to the passage inclosed by said frames, each of said frames having lateral air-outlet openings. 95

7. A furnace, a plurality of vertical partitions extending through a wall of the furnace forming fuel channels or retorts separated by intermediate spaces, horizontally reciprocating fuel-feeding pushers in said 100 retorts, and frames superposed upon one another between and at each side of said retorts, forming continuations thereof and defining the mouths of the retorts, said frames being open from top to bottom so as collectively 105 to form a continuous air passage, and having perforations in their rear ends for the outflow of air.

8. A furnace including a front wall, a plurality of fuel passages having vertical 110 side walls and extending in a generally horizontal direction through said front wall into the furnace inclosure, and frames superposed upon each other between the adjacent side walls of adjacent passages at the 115 mouths of said passages within the furnace, said frames being open from top to bottom so as collectively to form and inclose an air passage, and having openings for emission of air. 120

9. A furnace, in combination with a retort having vertical sides sloping at their rear ends and a horizontal bottom, a plurality of frames piled one upon another at the rear ends of such sides and in substantial continuation thereof, each frame being open from top to bottom and having emission offices at its rear portion; the frames forming collectively an air conduit with a multiplicity of outlets. 125 130

10. An air conduit section consisting of a frame having a continuous periphery constituted by two substantially parallel side members, a third member forming an end of the frame perpendicular to said side members, and an outwardly convexed rear member forming the opposite end of the frame and having transverse orifices.

11. A furnace, and, in combination there-
10 with a fuel passage having upright sides and a horizontal bottom, means for propelling fuel horizontally through said passage into the furnace, and an air conduit formed wholly of independent frames open from
15 top to bottom, placed one upon another at the rear and in continuation of the sides of the fuel passage, and having openings in their sides for the emissions of air.

12. A furnace, a fuel passage, a plurality
20 of frames forming the rear continuation of said passage, each consisting of parallel side members, a transverse front end member, and a convex rear end member, all in the same plane, forming a continuous outline
25 and inclosing an open space, said frames being superposed one upon another and forming and inclosing a continuous air passage, having openings in certain of their convex end members to permit outflow of air.

30 13. A furnace including in its construction fuel retorts and separated partitions forming the sides of said retorts, and removable frames superposed on one another in

rear of said partitions; said frames having sides extending in continuation of the partitions and forming continuations of the retorts, and the frames being also open from top to bottom and constituting air conduits for supplying air to the fuel, and having lateral outlets for emission of air.

14. A furnace, an underfeed stoker having fuel retorts, each of said retorts consisting of an independent casting separated by intermediate spaces from the adjacent retorts, fuel-feeding means in the forward 45 ends of said retorts, and removable frames placed one upon another between the rear ends of the retorts, collectively forming air conduits and having apertures in their sides.

15. A furnace, an air trunk having openings in its top side, a plurality of box-like retorts open at their rear ends secured to said air trunk, and separated by intermediate spaces from one another, each retort having an opening at its top for admission of fuel, 55 means for feeding fuel into and through the retorts, and frames placed in columns upon said trunk over the openings in the top thereof, at the rear ends of and between said retorts, to form rising air conduits.

In testimony whereof I have affixed my signature, in presence of two witnesses.
